UNITED STATES PATENT OFFICE.

JOHN M. YOUNG, OF SAN FRANCISCO, CALIFORNIA, ASSIGNOR TO AMERICAN CAN COMPANY, OF SAN FRANCISCO, CALIFORNIA, A CORPORATION OF NEW JERSEY.

CAN-BODY BLANK.

1,124,682.

Specification of Letters Patent.

Patented Jan. 12, 1915.

Original application filed October 31, 1912, Serial No. 728,928. Divided and this application filed May 9, 1914. Serial No. 837,425.

To all whom it may concern:

Be it known that I, JOHN M. YOUNG, a citizen of the United States, residing in the city and county of San Francisco and 5 State of California, have invented certain new and useful Improvements in Can-Body Blanks, of which the following is a specification.

The hereinafter described invention relates to an improved blank for use in connection with the manufacture of cans or metallic vessels for the hermetical sealing of food products, although the blank is designed more particularly for use in the 10 manufacture of that type of cans known unto the trade as "sanitary cans" or those wherein the end covers are double seamed onto a flanged end of the can body, the present application being a division of the application filed by me in the United States Patent Office on the 31st day of October, 1912— 15 Serial No. 728928, for an improvement in can bodies.

The objects of the invention are to so construct a blank that when the same is formed into a can body it will provide against the extreme end joint connections of the longitudinal side seam union breaking, separating, or pulling apart when the soldered can body is subjected to the action of the flanging rollers or devices for outwardly flaring or flanging the ends of the can body for the interlocking therewith of the can covers or end; reduce the thickness of the metal at 20 the said extreme end joint connections; provide for the formation of a better solder connection at such portions of the can body; materially increase the strength of the said end or lap joint sections of the can body; 25 provide against leaks at the extreme end joint connections of the said body, and in general materially improve the end joint union or connections of the lap portions at the ends of the side seam joint, and by 30 so doing, increasing the efficiency of the can, 35 body for the purposes desired.

Ordinarily, and more especially so where the union of the longitudinal edges of a can body blank when put into cylindrical form is made by what is known as a part lock and lap joint, seam union, the extreme end edges of the lap section of the can body are substantially co-extensive with the ends of the underlying section, and the end

edges of the said sections fall in the same 55 horizontal plane, with the result that when the closed and soldered lap portions of the can body are subjected to the action of the flanging mechanism for outwardly flaring the ends of the said can body, the lap sections of the side seam pull away from the underlying section at the corner edges of the side seam and break the solder union at such points and causes a bulging of the metal, and this breaking of the joint connection at the end corners of the joint union of the side seam and the bulging of the metal resulting therefrom not only seriously interferes with the proper double seaming of a can cover thereto, but oftentimes is the 60 cause of a leak at such points of the completed can. I have found from practical experience that if the extreme end corners of the end edges of the lap section of the can body blank be cut away and removed for a 65 distance slightly below the horizontal edge of the blank, there will be provided a clearance space at the extreme end or edge corners of the side seam of the formed can body and the said corner edges of the lap 70 section will terminate a short distance below the plane of the circumferential edge of the can body, forming end pockets which are filled with solder on the closed can body 75 being subjected to the action of the soldering mechanism, which solder is forced under the lap sections of the lap seam union and gives additional strength at such points of the side seam to resist or prevent the seam from opening or breaking apart under the 80 action of the mechanism for flanging the end of the can body and double seaming the covers thereto; also the extreme end corners of the ends of lap sections of the side seam being removed or lowered a 85 slight distance below the plane of the circumferential edge of the can body there is removed the slight projection which is ordinarily formed by the outside lap at the extreme ends of the side seam of the can body, 90 and which is crushed or mashed by the action of the flanging mechanism to such an extent as to distort and at times break the joint union at such points; again, by reason of the corner cut outs at the end corners of the lap or outside lap section of the can body blank there is on the blank 95 being formed into a can body less material 100

to be folded into the double seam at such points of the side seam of the can body on a cover being applied thereto, and equally so less material at such points to be outwardly turned during the flaring of the ends of the can body, all of which reduces the strain on the machines for flanging the ends of the can body and double seaming the covers thereto. Another advantage for 10 the notch or cut out formed at the extreme end corners of the lap or outside lap edge section of the can body blank is that, if the ends of the can body blank are not brought into perfect registry when formed into a 15 can body in the can making machinery so that one end stands slightly higher than the other, still, when the body is locked and soldered the ends of the outer portion or lap section of the body will not be above 20 the ends of the inner portion. This is a material help in the flanging of the ends of a can body, inasmuch as a formed and soldered body with one end slightly higher than the other will make imperfect flanging, 25 causing the outer part of the body to buckle or turn upward, producing imperfect double seaming, usually resulting in a leaky can.

To comprehend the invention, reference should be had to the accompanying drawings, wherein—

Figure 1 is a plan view of the improved body blank. Fig. 2 is a perspective view of a can body formed therefrom. Fig. 3 is a similar view of the can body after having 35 one of its ends flanged.

In the drawings, referring to Figs. 1, 2 and 3 thereof, the numeral 1 designates the metallic blank, 2 and 3 the locking edge portions of the blank, and 4 and 5 the end lap sections of the locking edge portions. The end lap or outside lap sections 4 are formed with a cut out 6 to place the extreme end corners thereof a slight distance below the plane of the horizontal edge 6' of the blank, 40 so that when the blank is formed into a can body 7 there is produced a pocket 8 at the upper corner of each end of the side seam 9, the end or corner 10 of each lap end of the side seam 9 of the can body being situated at 45 a point a slight distance below the plane of the circumferential edge 10' of the ends of the can body. As thus placed, there is no edge corner at the ends of the side seam to be acted on by the flanging mechanism to be torn apart, separated or bulged outwardly 50 by the strain placed onto the metal during the out-turning thereof, and the pockets 8 formed by the cut out 6 provide a space for

the reception of solder which is forced into the lap seam sections when subjected to the 60 action of the soldering mechanism in a much better manner than heretofore and which serves as added strength at such points of the side seam of the can body and prevents the lap sections of the side seam from opening up under the act of flanging the ends of the can body and double seaming the covers onto the same.

With the use of the improved blank for the formation of a can body there is no distortion of the ends of the side seam nor is the same broken, separated or torn apart at the end corners during the flanging operation, which is an important feature in connection with the double seamed sanitary 75 cans, inasmuch as it reduces imperfect and leaky cans to a minimum.

While the invention has been illustrated and described for use in connection with what is known as a combined locked and 80 lap joint side seam, its use is not so limited or restricted, inasmuch as it is equally applicable to a lap or to a lock side seamed can body, and it is to be understood that by the expressed lap joint reference is had to the 85 end portions of the side seam and this irrespective as to what form of joint union is made intermediate such portions of the side seam. The essential feature of the invention and that desired to be covered broadly resides in cutting away the extreme edge corner of the outside lap section of the blank to place the same, when the blank is formed into a can body, below the plane of the circumferential edge of the said can body. 90

Having thus described the invention what is claimed as new and desired to be protected by Letters Patent is:—

A can body blank provided at one side edge with end lap sections, a projecting side seam section intermediate the said end lap sections, and a cut out formed in the upper corner edge of each of the outside lap sections of the blank, whereby the lower edge of each cut-out of said end corner of each lap section when the blank is formed into a can body is placed a slight distance below the upper edge of the opposing lap sections.

In testimony whereof I have signed my name to this specification in the presence of two subscribing witnesses.

JOHN M. YOUNG.
